UNITED STATES PATENT OFFICE

162,514

LAPEL BUTTON OR SIMILAR ARTICLE

George A. Bronson, Council Bluffs, Iowa

Application September 12, 1950, Serial No. 12,154

Term of patent 3½ years

(Cl. D29—2)

To all whom it may concern:

Be it known that I, George A. Bronson, a citizen of the United States, residing at Council Bluffs, in the county of Pottawattamie and State of Iowa, have invented a new, original, and ornamental Design for a Lapel Button or Similar Article, of which the following is a specification, reference being had to the accompanying drawing, forming part hereof.

Figure 1 is a front elevational view of a lapel button or similar article, showing my new design;

Figure 2 is a cross sectional view thereof taken substantially on the plane of the line 2—2 looking in the direction of the arrows; and

Figure 3 is a side elevational view of the same.

I claim:

The ornamental design for a lapel button or similar article, as shown.

GEORGE A. BRONSON.
